(57) **CLAIM**

The ornamental design for a label printer, as shown and described.

DESCRIPTION

The file of this patent contains at least one drawing/photograph executed in color. Copies of this patent with color drawing(s)/photograph(s) will be provided by the Office upon request and payment of the necessary fee.

1. Label printer

1.1 : Perspective

1.2 : Front

1.3 : Back

1.4 : Top

1.5 : Bottom

1.6 : Right

1.7 : Left

1.8 : Enlarged

The evenly spaced and dot-dot-dash broken lines in the figures are directed to environment and form no part of the claimed design.

The dashed dotted lines in the figures denote the boundary of the claim and form no part of the claimed design.

The color blue forms part of the claimed design.

1 Claim, 8 Drawing Sheets
(3 of 8 Drawing Sheet(s) Filed in Color)
